MATERIAL HANDLING MECHANISM

Nils D. Levin and Edward G. Lewis, Columbus,
Ohio, assignors to The Jeffrey Manufacturing
Company, a corporation of Ohio

Original application August 19, 1930, Serial No.
476,390. Divided and this application Janu-
ary 24, 1935, Serial No. 3,278

15 Claims. (Cl. 198—8)

Our invention relates to track mounted loading machines particularly of the type adapted for use in coal mines. One of the objects of our invention is the provision of improved and efficient means for maintaining in predetermined relation with the mine track, the receiving portion of a conveyor which is adapted to be adjusted on an upright axis.

Another object of the invention is to combine with the forward receiving end of a swinging conveyor, abutment mechanism for engaging the rails of a mine track to hold the conveyor in predetermined relation with the mine track while such conveyor is receiving material to be loaded into mine cars.

A further object of the invention is the provision of improved and efficient rope gearing for operating a gathering conveyor by swinging the same arcuately on an upright axis while delivering gathered material to a receiving conveyor.

More particularly it is the object of our invention to provide a pair of shoes or plates having pin-receiving holes carried by the receiving end of a swinging conveyor and adapted to receive pins in position to engage the rails of a mine track to prevent lateral movement of the conveyor while receiving material from a swinging gathering conveyor operating in advance of the mine track.

Other objects of the invention will appear hereinafter, the novel features and combinations being set forth in the appended claims.

In the accompanying drawings,

Fig. 1 is a side elevational view of the front end of the loading machine showing the swinging gathering conveyor section;

Fig. 2 is a side elevational view of the rear portion of the loading machine, the complete loading machine being illustrated in Fig. 2 and Fig. 1, placed end to end;

Fig. 3 is an enlarged plan view of that portion of the loading machine where the gathering section delivers material to the discharge section;

Fig. 4 is a diagrammatic plan view showing the loading machine completing a sumping gathering operation by propelling the entire loading machine along the mine track;

Fig. 5 is a diagrammatic plan view illustrating the operation of the improved rope gearing acting to swing the gathering conveyor about a vertical axis while remaining in delivery communication with the receiving conveyor;

Fig. 6 is a transverse sectional view taken on the line 6—6 of Fig. 2, looking in the direction 55 of the arrows; and

Fig. 7 is a side elevational view of the loading machine with the gathering unit mounted on a pony truck for transportation along narrow and curved entries in a coal mine.

This application is a division of our co-pending application Serial No. 476,390, filed August 19, 1930, now Patent No. 1,997,590, for improvement in Material handling mechanism, in which we have described and claimed the various elements of the loading machine in combination, and more particularly the adaptation thereto of the structure illustrated in Fig. 6 of the accompanying drawings; whereas the present application is directed to the sliding supporting shoes and the abutment pins associated therewith and the combination of such abutment mechanism with the rope gearing for swinging the gathering conveyor C, as illustrated diagrammatically in Fig. 5.

Referring to the accompanying drawings and particularly to Figs. 1 and 2, A designates generally a self-propelling truck which supports a receiving conveyor B which in this instance is also the discharge conveyor for delivering material to mine cars. The conveyor B is mounted on the truck A for pivotal movement relatively thereto about both vertical and horizontal axes. The conveyor B comprises two sections B' and B'' relatively adjustable on a transverse horizontal axis, as will be described hereinafter.

Pivotedly connected upon an upright axis to the front end of the conveyor B is a gathering conveyor C which, for transportation along the mine tracks, is adapted to be supported on a pony truck D, as shown in Fig. 7. When in operating position off the pony truck D and on the mine bottom in advance of the mine truck A, the gathering conveyor C may be dumped into the coal which has been dislodged from the coal face, as illustrated in Fig. 4. During such dumping operation, the endless traveling conveyors of both the sections B and C may be operated to deliver coal to the mine car F as shown in Fig. 4. The rope gearing may be arranged as shown in Fig. 5 when the gathering conveyor C is swung arcuately along the mine bottom while delivering coal to the discharge conveyor B and while the forward receiving end of the latter is held against lateral movement relatively to the truck A and the mine track E, by means of the pin abutment mechanism hereinafter more fully described.

The truck propelling mechanism comprising the flexible transmission means between the motor on the turntable and the truck wheels while the discharge conveyor occupies various angular positions, is described and claimed in the co-

pending application of Nils D. Levin, Serial No. 386,647, filed August 17, 1929, for an improvement in Pit car loaders.

As shown in Fig. 2, truck A comprises a frame 10 supported on wheels 11 and 12 mounted on axles 13 and 14, the flanged wheels being designed for travel along the mine track E. Mounted on said frame 10 is a platform having a turntable frame 18 which is attached thereto for pivotal movement about a vertical axis, as illustrated at 17, 19, 20 in Fig. 6. The bottom 19 of the frame 18 contacts with the top 15 of the frame 10 over a relatively wide area, and consequently the annular groove at the pivotal connection located at 15 the top of the plate 15 and formed by means of the rings 17 and 20 is effective in preventing tilting of the frame 18 relatively to the frame 10. Consequently the flexible drive chain 44 is maintained in such position as to permit the discharge conveyor B to be moved through a wide angle on the vertical axis of the pivotal connections between the frames 10 and 18.

A motor 21 is mounted on the frame 18 with its armature shaft extending transversely thereof. The armature shaft has secured thereon a sprocket 22 which through a chain 23 drives a sprocket 24 mounted on a shaft 25 parallel to the armature shaft. The upper run of the chain 23 engages an idler pulley 26, as shown in Fig. 2.

At its end opposite sprocket 24, the shaft 25 has secured thereto a second sprocket which engages a chain 27 to drive a sprocket 28 fixed to a hub 29, as shown in Fig. 6. The hub 29 is mounted on the shaft 30 for free rotation thereon. The shaft 30 is journaled in the upper portion of the frame 18 in parallel relation to the shaft 25. A shiftable clutch element 31 is splined on shaft 30 and is provided with teeth 32 for engagement with teeth 33 on the hub 29 so that rotation of the latter will be imparted to the shaft 30. That is to say, when the motor 21 is operating, power will be transmitted therefrom through the sprocket chain gearing, shown in Fig. 2, and the shaft 25, to the sprocket 28 shown in Fig. 6, and when the clutch 31 is thrown in, power will be transmitted to the transverse shaft 39.

Fixed on the shaft 30 within and adjacent the side walls of the frame 10 is a pair of sprockets 34, 35 which are adapted to engage the lower runs of the chains 36, 37 of the scraper conveyor comprising the cross flights 38. This scraper conveyor travels the full length of the bed or way of the discharge conveyor B, as illustrated in Fig. 5.

A second shaft 39, as shown in Fig. 6, is journaled in the frame 18 below the shaft 30 and is adapted to be driven by the sprocket chain 41 and the sprockets 40, 42. It will thus be seen that this shaft 39 always rotates in unison with the shaft 25 whenever the clutch 31 is thrown in. That is to say, when the motor 21 is operated and the clutch 31 is thrown in, power will be transmitted to the shaft 39 to drive the endless scraper conveyor of the discharge conveyor B, and at the same time power will be transmitted from the shaft 25 through the shaft 30 to the transverse shaft 39.

Freely journaled on the second shaft 39 is a drive sheave 43 with which is engaged a universal chain 44 extending downwardly through the circular opening 16 in the top plate 15 of the frame 10. In other words, the endless chain 44 extends downwardly from the sheave 43 through the pivotal connection between the frames 10 and

15 at the axis of pivotal adjustment between these frames. The chain 44, as shown in Fig. 2, extends around the idler pulleys 45 and 46 and thence around the driving sheaves 47 mounted on the axles 13 and 14 of the truck. An appropriate clutch 50 having clutch elements 48, 49, as shown in Fig. 6, is provided for connecting the transverse shaft 39 to the drive sheave 43 when the entire loading machine is to be propelled along a mine track either for the sumping operation, as shown diagrammatically in Fig. 4, or for transportation purposes, as illustrated in Fig. 7.

As illustrated in Figs. 2 and 6, the shaft 39 carries at one end a cone clutch element 54 adapted to co-operate with the cone clutch element 58 of winding drum 57 around which is adapted to be wound a rope or cable 170 for operations hereinafter more fully explained. An operating lever 14 (Fig. 2) is provided for actuating the lever 63 connected to the shipper 65, 66, as shown in Fig. 6. This shipper 65, 66, is connected by means of the tongue and groove mechanism shown in Fig. 6 at 60, 61 and the ball-bearing shown at 64, to the rope drum 57 so as to enable the operator by means of the lever 14 to apply or release the cone clutch 54, 58 to control the rope drum 57.

Connected to the rope drum 57 to rotate therewith is a brake drum 59 adapted to co-operate with brake mechanism including the operating lever 87 shown in Fig. 2. This lever has a plurality of teeth adapted to be engaged selectively by a pawl 88 to retain said braking mechanism in locked positions of adjustment and thereby lock the winding drum in stationary position whenever desired.

From the foregoing description, it will be evident that when the clutch 31 shown in Fig. 6, is thrown in, the endless scraper conveyor of the conveyor B will be operated as illustrated in Fig. 4. When the clutch 50 is thrown in, the truck propelling mechanism will be operated to move the entire machine along the mine track. It should be particularly noted, however, that only when the clutch 31 is thrown in is the endless conveyor of the conveyor B operated. When the clutch 31 is released, power may nevertheless be transmitted from the motor 21 to the shaft 39, and therefore when the clutch 50 is thrown in, while the clutch 31 is released, the whole machine may be moved along a mine track without operating the conveyor B. This arrangement is desirable for the transportation illustrated in Fig. 7.

The winding drum 57 may be operated independently of the operation of the conveyor B and independently of the operation of the truck propelling mechanism because when the motor 21 is operated there will be a direct transmission of power through the shafts 25 and 30 to the transverse shaft 39. Consequently, when the clutch 54, 58 is thrown in, the rope drum 57 may be operated to hoist the gathering unit on to the pony truck while the conveyors and the truck propelling mechanism are out of operation. However, simultaneous operation of the gathering conveyor C, the discharge conveyor B and the rope drum 57 may be secured whenever the gathering conveyor C is operated, as illustrated in Fig. 5, to effect gathering of the coal and the delivery thereof to the mine car F.

As shown in Figs. 1 and 2, the adjacent portions of the conveyor sections B' and B'' constitute an inclined portion having at its upper end a substantially horizontal prolongation and at its other end another substantially horizontal

extension adjacent to the mine track. To each side of the section B'' at its upper end is attached an arm, one of which is shown at 91 in Fig. 2, the arms extending along the adjacent end of the conveyor section B' and supporting a pin 92 upon which section B' is tiltably mounted. Each arm 91 has a threaded rod 93 pivoted to its upper extremity, and each rod is provided at its lower end with a nut 94. The rod extends through an aperture in a bolster 95 on the underside of the section B'. Each rod 93 has a compression spring 96 mounted thereon between the bolster 95 and the nut 94. The section B' is thus resiliently supported on the bolster 95 and its position relative to the section B'' may be adjusted as desired by appropriate adjustment of the nuts 94. The conveyor B as a whole is supported for tilting movement about the horizontal transverse shaft 30 shown in Figs. 2 and 6, so that the lower receiving end of the conveyor B may rest upon the track E, or may be elevated for transportation. An apron 103 is so disposed, as shown in Fig. 2, as to guard the lower runs of the endless scraper conveyor of the conveyor B, from interference 25 with the underlying parts of the machine.

At the forward end of the inclined portion of section B'' are secured plates or shoes 97 and 98 as shown in Figs. 2 and 3. Each of these plates or shoes has a forward portion formed by the 30 plate being U-shaped to provide horizontal spaced-apart flat sections 97' and 98', each of which is provided with a plurality of aligned apertures 99 and 100 through which may be extended pins 101 and 102 to project below the plates or 35 shoes into engagement with the sides or balls of the track rails to prevent lateral displacement of the receiving conveyor B relative to the mine track or relative to the truck during the gathering operations illustrated in Fig. 5.

The plates or shoes 97 and 98 are important 40 features of our invention as they serve the double function of supporting the forward end of the conveyor B on the rails of the track E when the loading machine is in operation as illustrated in Fig. 5, and of also preventing lateral movement 45 of the lower receiving end of the conveyor B relatively to the mine track during the swinging of the gathering conveyor. That is to say, the pins 101 by engaging the balls of the rails, counteract the tendency of the swinging of the gathering conveyor C, to swing the receiving conveyor B on its vertical axis relative to the truck, when the machine is operating as illustrated in Fig. 5.

It should also be noted that the rope gearing 55 for swinging the gathering conveyor C is arranged for most efficient operation as illustrated in Fig. 5. The rope 170 which extends from the rope drum 57 is guided around an idler sheave 104 which is mounted at the rear end plate 97. The plate 98 60 supports in a similar manner an idler sheave 106 on the other side of the machine, as shown in Fig. 5.

As shown in Fig. 5, the gathering conveyor C 65 is performing a coal gathering operation by being swung about its pivotal connection to the conveyor B. In this operation, the plates or shoes 97 and 98 and their pins 101 and 102 perform the double function of supporting the forward end of the discharge conveyor B and of preventing lateral movement thereof relatively to the truck. To effect the swinging movement of the gathering conveyor C, the free end of the cable 170 is attached to the pocket terminal 139 shown at the 70 upper end of the post 137 in Fig. 1. The cable

170 is reeved through a pulley attached to a mine roof jack at 181. By referring to Fig. 5, it will be seen that the pulls exerted on the sections of the rope extending from the mine roof jack 181, are such as to efficiently swing the gathering conveyor on its pivotal connection with the discharge conveyor B while the receiving end of the latter remains above the mine track, because the pull on the rope is effectively resisted by the pins 101 engaging the rails. By placing the idler 10 10 sheaves 104 and 106 between the truck and the pins 101, the pulling strain on the pins 101 is relieved by the truck. That is to say, the pins 101 and the truck co-operate in serving to afford an anchorage for that section of the rope 170 15 which extends between the idler sheave 104 and the roof jack 181.

To swing the gathering conveyor C in a direction opposite to that shown in Fig. 5, the mine roof jack 181 will be placed on the other side of 20 the machine and the cable 170 extended across the under side of the section B'' by being reeved around the idler sheaves 105, 106 instead of around the idler sheave 104 alone. Otherwise, the operation of the rope gearing is the same as 25 that already described.

As shown in Fig. 2, a panel 109 is supported 30 between uprights 107 and 108 on an intermediate portion of the frame of the conveyor section B''. Various electrical control appliances are mounted on the panel 109. At the upper end of the arm 108 is mounted a sheave 110 on a horizontal axis, and spaced inwardly of the sheave 110, as shown in Fig. 3, is a bracket 111 provided with an open jaw for receiving the free end of the rope 35 170. On the other side of the machine opposite the sheave 110 is a sheave 112 rotatably mounted on the vertical axis on the bracket 113.

To the forward end of the conveyor section B'' 40 is pivoted on a pivot member 114 disposed on the central longitudinal line of the conveyor section B'', a bracket or member 115 comprising sections 116 and 117. The bracket 115 is adapted to swing from one side of the forward end of the section B'' to the other. A horizontal angle bar 45 118 secured adjacent to the extremity of the bracket portion 117 has a depending lug 119 adapted to engage behind an arcuate rail 120 formed on a flange 121 secured to the conveyor section end. The pivot member 114 is concentric 50 with the arcuate rail 120. Extending transversely of the upper end of portion 117 opposite the angle bar 118 is a channel member 122, while at the lower extremity of portion 117 is a fixed shoe 123. It will thus be seen that the gathering conveyor C is connected to the section B'' of the conveyor B on a vertical axis at 114, and is also connected to the section B'' on a horizontal axis at 55 141. The flexibility of these connections between the gathering conveyor C and the conveyor section B'' comes into play in the operation illustrated in Fig. 5 as well as when the machine is being transported in the mine. For transportation purposes a tilting movement on the horizontal axis 141 takes place for adjustment to the positions of the parts illustrated in Fig. 7, and when the machine is being transported along curves of a mine track, the conveyor B is free to move on its vertical axis relative to the truck, the conveyor C is free to move on its vertical axis relative to the pony truck D, and the two conveyors B and C are free to move relatively to each other on the vertical axis 114 (Figs. 1 and 7).

As shown in Fig. 1, the gathering conveyor C 75

comprises a horizontal portion C' and an inclined portion C''. A base plate 124 extends over the entire bottom of the conveyor C and has disposed thereon suitable guide members as at 125 and 126 for an endless flight conveyor chain 127 flexible both horizontally and vertically. The conveyor chain 127 is adapted to advance along that side of the plate 124 which acts to scrape the material from the mine bottom for delivery to the conveyor B. The flights 128 are connected to the chain 127 at intervals and are adapted to engage the loose material from the mine bottom and move it along the base plate 124 for discharge from the upper extremity of the inclined section C''. The flights 128 are freely exposed laterally on the portion C' of the conveyor C. Material retaining side walls 129 and 130, as shown in Fig. 3, are provided along the inclined edges of the section C''.

20 The conveyor head shaft 131 of the conveyor C as shown in Fig. 1, has a sprocket fixed thereto, meshing with the chain 127 to drive the latter. A foot sprocket is arranged on a shaft 132 at the outer end of the plate 124. Also secured 25 to the shaft 131 is a bevel gear 133 with which meshes a drive pinion 134 which in turn is driven from the armature shaft of the motor 135 mounted on a suitable base supported on the plate 124 intermediate the runs of the chain 127. Extending forwardly from the motor 135 and centrally of the plate 124 is an upright baffle plate 136, at the outer extremity of which is located an upright post 137 having a bifurcated upper extension to provide the rope attaching pocket 139.

20 The conveyor head shaft 131, plate 124 has secured thereto a bracket having spaced side walls of which one is shown at 140 (Fig. 1) projecting downwardly and adapted to receive channel 122 between them. Walls 140 are perforated to receive a removable pin 141 which is adapted to extend through channel 122 to unite the gathering conveyor C with mounting member 115, already described.

45 It will be evident that conveyor C may be adjusted relative to conveyor B about an axis defined by pivot member 114 and about a horizontal axis defined by pin 141. Due to the spaced relation of pin 141 to the top and bottom walls 50 of channel 122, conveyor C may also be adjusted relative to conveyor B about a longitudinally extending axis. The upper end of conveyor C is normally supported on the upper end of bracket portion 117 on a rocking block or bolster 142.

55 In operation, portion C' of the gathering conveyor C assumes the position shown in Fig. 1 wherein it is adapted to rest directly on the mine floor and to be swung thereover in the manner which will be described more in detail hereinafter. When the machine is to be transported, 60 the gathering conveyor is supported on a pony truck which is pivotally attached to said gathering conveyor by the cup 154. (Fig. 7.)

Inasmuch as the gathering conveyor is of considerable weight, it is desirable to provide motor operated means for elevating it into such position as to enable the pony truck to be placed thereunder. A casting 155 secured to base plate 124 forwardly of head shaft 131, has a pair of spaced upwardly projecting ears 156 and 157 which support a pin 158 which extends transversely of the plate. (See Figs. 1 and 3.) A member 159 comprising two parallel arms is pivoted at one end on pin 158 and at its other end has a bail 75 160 pivoted thereto by means of a pin 161. A

cable 162 secured to the bail is passed forward through aperture 138 of post 137 and secured, the cable when taut permitting member 159 to take the position shown in Fig. 1. Intermediate the upper ends of the arms comprising member 159, 5 a block 163 is mounted on pin 161 (Fig. 3), this block revolvably supporting a pair of sheaves 164 and 165. A tubular member 166 is pivoted at 167 to a casting on the motor frame and projects rearwardly between the arms of member 159. 10 Rearwardly of member 159, member 166 is provided with a downwardly projecting longitudinally slotted web 168 in the slot of which is engaged a removable pin 169 extending between and supported by the arms of member 159. Abutment 15 of pin 169 with the lower end of the slot of web 168 serves to hold member 159 in the upright position of Fig. 1 and also serves to hold member 166 in the position shown in Fig. 1, members 159 and 166 thus acting as mutual props. 20

Referring to Figs. 1 to 3, a rope or cable 170 is adapted to have one of its ends engaged with winding drum 57. Thence the cable is adapted to be trained forwardly over sheave 110, thence around sheave 165, rearwardly to and around 25 sheave 112, again forwardly and around sheave 164, and finally rearwardly again to be anchored between jaws 111. It will be evident that upon rotation of winding drum 57 in the winding direction and consequent tensioning of rope 170, a 30 substantially horizontally directed pull will be exerted on conveyor C about pivot pin 141, due to the attachment of block 163, which supports sheaves 164 and 165, to the upper end of member 159. Tensioning of cable 162 will arrest any 35 tendency of member 159 to swing about pin 158, and it will therefore be evident that the forward end of conveyor C will be swung upwardly.

The pony truck D comprises a circular ring 149 mounted rigidly on a wheeled truck at the 40 center of which is an upwardly projecting pin having a semispherical head adapted to fit into the cup-shaped socket 154 secured to the bottom of the gathering conveyor C, as shown in Figs. 1 and 3. When the tension on the hoisting rope 45 170 is released as illustrated in Fig. 7, the gathering conveyor will be supported by the ball and socket joint 148, 154 and the ring 149, while the overhanging weight of the conveyor C in advance of the pony truck D will by means of the pivotal 50 connection at 141 to the conveyor section B'', lift the latter clear of the mine track for transportation in the mine. During transportation along curved portions of the mine track in narrow mine entries, the discharge conveyor B will 55 be free to swivel on its pivot 16, 17, 20 (Fig. 6) relatively to the truck A, the gathering conveyor will be free to swivel on the ball and socket joint 148, 154 (Fig. 7) while sliding arcuately on the ring 149, and the two conveyors B and C will be 60 free to swivel relatively to each other on the vertical pivot 114 (Fig. 1) between the same.

The controller for motor 135 is disposed on panel 109 and novel means are provided for supporting the electrical conductors intermediate 65 the controller and the motor.

Vertically reciprocable in bearings 171 and 172 on upright 107 is a tubular member 173 having a horizontal projecting upper extension 174 whose extremity is outwardly flared. Conductor cable 70 175 is trained through the tubular housing constituted by portions 173 and 174 and thence is passed through tubular member 166 to the motor 135, the free extremity of member 166 being outwardly flared.

During operation of the gathering conveyor, it is desirable that the cable portion intermediate the two tubular supports be elevated so as not to interfere with the passage of material from one conveyor to the other and such disposition is illustrated in Figs. 1 and 2, member 166 being maintained in the position shown by the means already described.

Bearing 171, on the other hand, is provided with a recess adapted to be engaged by a lug 177 on tubular member 173; the lug, when so positioned, being engageable by a latch 178 hung on bearing 171. It will be evident that the walls of the recess engaging the lug, prevent rotation of element 173 and thereby prevent accidental disengagement of the lug from the latch, the latter serving to hold the tubular guide element in the position of upward adjustment shown in Fig. 3.

Referring particularly to Figs. 4 and 5, there are seen diagrammatic illustrations of two of the many different operations which may be performed by our device. As seen in Fig. 4, a sumping operation is being completed after the coal has been cut and shot down. Loose coal at 155 is gathered by the gathering conveyor C and delivered to discharge conveyor B from which it is discharged into a mine car F. In this operation, the plates or shoes 97 and 98 while supporting the forward end of discharge conveyor B act in cooperation with the pins 101 and mine track rails, to prevent buckling of the loading machine conveyors. To effect this sumping operation, while the gathering conveyor C is held in alignment with the discharge section B, the cable 170 is reeved about the horizontal pulley 104 and the free end of the cable 170 is anchored to a suitable mine jack at 180 (Fig. 4). The entire machine is then sumped into the coal by operating the friction clutch 54, 58 to connect drum 57 to the motor 21. At the same time, motor 21 drives the flights of discharge conveyor B and motor 135 drives the flights of gathering conveyor C.

It should be particularly noted that the truck propelling mechanism is sufficiently flexible to permit lateral adjustment of the receiving conveyor through an angle of about 45° on each side of the mine track. When the gathering conveyor C is to be operated in very wide entries or rooms in advance of the mine track, it is desirable to run the shoes off the ends of the mine track and swing the conveyor apparatus B, C on the vertical axis of the turntable relatively to the truck so as to secure a greater reach for the gathering conveyor C. When the conveyor apparatus is thus adjusted at an angle to the mine track, the shoes may rest on the mine bottom and the pins extending through the shoes driven into the mine bottom particularly if their lower ends are sharpened for this purpose. If, however, the mine bottom is composed of material which is too hard to permit free driving of the pins into the mine bottom, a roof jack may be used at one side of the section B'' as an abutment, or such roof jack may be used between the roof of the mine entry or room and one of the shoes so as to anchor the latter firmly to the mine bottom. Furthermore, the anchoring jack 181 may be set in such a position that the pull on the rope between the conveyor section B'' and the vertical post at the outer end of the gathering conveyor will be nearly at right angles to the latter, whereas that portion of the rope extending from the side of the section B'' to the anchoring jack 181 will be nearly parallel to the

conveyor B. There will then be little tendency to swing the receiving portion B'' sidewise, while at the same time considerable force will be exerted in swinging the gathering conveyor on its pivotal connection 114 to the lower receiving end 5 of the conveyor section B''. This is particularly true if the pulling rope 170 is extending under and transversely across the bottom of the section B'' by being reeved around the pulleys 105, 106 and the connection to the gathering conveyor so made as to swing the latter anti-clockwise, instead of clockwise as shown in Fig. 5.

Obviously those skilled in the art may make various changes in the details and arrangement of parts without departing from the spirit and scope of the invention as defined by the claims hereto appended, and we wish therefore not to be restricted to the precise construction herein disclosed.

Having thus described and shown an embodiment of our invention, what we desire to secure by Letters Patent of the United States is:

1. In a machine of the class described, a truck having wheels adapted to engage a track, a conveyor frame pivotally mounted on said truck on a transverse horizontal axis and having an end portion extending in proximity to the track at one end of the truck, and laterally extending plates on said end portion of the conveyor adapted to rest upon the rails of the track to support the weight of said extending portion, said plates being provided with downwardly projecting means adapted to abut the track rails to prevent displacement of the plates transversely of the rails. 35

2. In a machine of the class described, a truck having wheels adapted to engage a track, a conveyor frame pivotally mounted on said truck on a transverse horizontal axis and having an end portion extending in proximity to the track at one end of the truck, and laterally extending plates on said end portion of the conveyor adapted to rest upon the rails of the track to support the weight of said extending portion, said plates being provided with a plurality of spaced apertures and pins selectively insertable in said apertures to project beneath the plates for lateral abutment with the track rails to prevent displacement of the plates transversely of the rails. 45

3. In a loading apparatus, the combination with a receiving conveyor, of a track mounted truck for supporting said conveyor with one end in a position adjacent the track, a gathering conveyor pivotally attached to said receiving conveyor at said one end and means comprising a substantially horizontal plate and a downwardly projecting pin attached to said one end of said receiving conveyor, said plate being adapted to rest on said track while the pin projects downwardly below the top thereof to cooperate with 60 said track to prevent lateral movement of said one end of said receiving conveyor. 55

4. In a loading apparatus, the combination with a receiving conveyor, of a track mounted truck for supporting said conveyor with one end 65 in a position adjacent the track, a gathering conveyor pivotally attached to said receiving conveyor at said one end for pivotal movement about a vertical axis, and means attached to said one end of said receiving conveyor adapted to cooperate with said track to support said one end of said conveyor and to prevent lateral movement thereof, said means comprising a pair of substantially horizontal plates and downwardly projecting pins, one for each track rail. 70

5. In a loading apparatus, the combination with a receiving conveyor, of a track mounted truck for supporting said conveyor with one end in a position adjacent the track, a gathering conveyor pivotally attached to said receiving conveyor at said one end for pivotal movement about a vertical axis, means for moving said gathering conveyor about said axis to gather material, and means attached to said one end of said receiving conveyor adapted to cooperate with said track to prevent lateral movement thereof, said means comprising a plate having a plurality of holes and a pin selectively receivable by any one of said holes.
15. 6. In a loading apparatus, the combination with a receiving conveyor, of a track mounted truck for supporting said conveyor with one end in a position adjacent the track, a gathering conveyor pivotally attached to said receiving conveyor at said one end for pivotal movement about a vertical axis, means for moving said gathering conveyor about said axis to gather material, and means attached to said one end of said receiving conveyor adapted to cooperate with said track to prevent lateral movement thereof, said means comprising a pair of plates each having a plurality of holes and pins selectively receivable by said holes.
25. 7. In a loading apparatus, the combination with a receiving conveyor having an elevated material discharge end and a lowered material receiving end, of a truck positioned intermediate the ends of said conveyor for supporting said conveyor for pivotal movement about a horizontal axis, a gathering conveyor pivotally attached to said lowered end of said receiving conveyor adapted to feed said receiving conveyor and mounted for pivotal movement about a vertical axis, means for moving said gathering conveyor about said vertical axis to gather material, and means for supporting said lowered end of said receiving conveyor and for preventing lateral movement thereof comprising a plate having an aperture therein and a pin adapted to be inserted in said aperture.
35. 8. In a loading apparatus, the combination with a receiving conveyor having an elevated material discharge end and a lowered material receiving end, of a truck positioned intermediate the ends of said conveyor for supporting said conveyor, a gathering conveyor pivotally attached to said lowered end of said receiving conveyor adapted to feed said receiving conveyor and mounted for pivotal movement about a vertical axis, means for moving said gathering conveyor about said vertical axis to gather material, and means for supporting said lowered end of said receiving conveyor and for preventing lateral movement thereof comprising a plate having an aperture therein and a pin adapted to be inserted in said aperture.
45. 9. In a loading apparatus, the combination with a receiving conveyor having an elevated material discharge end and a lowered material receiving end, of a track mounted truck for supporting said conveyor for pivotal movement about a vertical axis, a gathering conveyor pivotally attached to said lowered end of said receiving conveyor adapted to feed said discharge conveyor and mounted for pivotal movement about a vertical axis, means for moving said gathering conveyor about said vertical axis to gather material, and means for supporting said lowered end of said receiving conveyor and for preventing lateral movement thereof comprising a pair of plates having a

plurality of apertures and pins adapted to be inserted in selected ones of said apertures to position the lowered end of the receiving conveyor at any one of a plurality of positions relative to said track.

5. 10. In a loading apparatus, the combination with a receiving conveyor having an elevated material discharge end and a lowered material receiving end, of a track mounted truck for supporting said conveyor, a gathering conveyor pivotally attached to said lowered end of said receiving conveyor adapted to feed said receiving conveyor and mounted for pivotal movement about a vertical axis, means for moving said gathering conveyor, and means for supporting said lowered end of said receiving conveyor and for preventing lateral movement thereof comprising a pair of substantially horizontal plates each having an aperture and a downwardly extending pin adapted to be inserted in said aperture.

15. 11. In a loading apparatus, the combination with a receiving conveyor, of a track mounted truck for supporting said conveyor with one end in a position adjacent the track, a gathering conveyor pivotally attached to said receiving conveyor at said one end for pivotal movement about a vertical axis, means for moving said gathering conveyor about said vertical axis to gather material, and means attached to said one end of said receiving conveyor adapted to cooperate with said track to support one end of said receiving conveyor and to prevent lateral movement thereof, said means comprising a shoe having a pair of vertically spaced walls provided with aligned holes and a pin adapted to project downwardly through said aligned holes and to be positioned laterally of said track.

25. 12. In a loading apparatus, the combination with a receiving conveyor, of a track mounted truck for supporting said conveyor with one end in a position adjacent the track, a gathering conveyor pivotally attached to said receiving conveyor at said one end for pivotal movement about a vertical axis, means for moving said gathering conveyor about said vertical axis to gather material, and means attached to said one end of said receiving conveyor adapted to cooperate with said track to prevent lateral movement thereof, said means comprising a shoe having a pair of vertically spaced walls provided with a plurality of aligned holes and a pin adapted to project downwardly through selected ones of said aligned holes and be positioned laterally of said track.

35. 13. In a loading apparatus, the combination with a receiving conveyor, of a track mounted truck for supporting said conveyor with one end in a position adjacent the track, a gathering conveyor pivotally attached to said receiving conveyor at said one end for pivotal movement about a vertical axis, means for moving said gathering conveyor about said vertical axis to gather material, and means attached to said one end of said receiving conveyor adapted to cooperate with said track to support one end of said receiving conveyor and to prevent lateral movement thereof, said means comprising a pair of shoes, one for each track rail, each having a pair of vertically spaced walls provided with a plurality of aligned apertures and a pin adapted to project downwardly through selected ones of said aligned apertures and be positioned laterally of said track.

45. 14. In a loading apparatus, the combination with a receiving conveyor, of a track mounted truck for supporting said conveyor with one end in a position adjacent the track, a gathering

conveyor pivotally attached to said receiving conveyor at said one end for pivotal movement about a vertical axis, means for moving said gathering conveyor about said vertical axis to gather material, and means attached to said one end of said receiving conveyor adapted to cooperate with said track to prevent lateral movement thereof, said means comprising a pair of shoes, one for each track rail, each having a pair of vertically spaced walls provided with aligned holes and a pin adapted to project downwardly through said aligned holes and be positioned laterally of said track.

15. In a loading machine, the combination with

a truck movable along a trackway, of a receiving conveyor mounted thereon and extending downwardly and forwardly into proximity to said trackway, abutment mechanism between said forwardly extending portion of said conveyor and said trackway, a gathering conveyor connected to said receiving conveyor to swing relatively thereto on an upright axis in advance of said trackway, and rope gearing connected to said abutment mechanism and operative to swing said gathering conveyor as aforesaid to gather material for delivery to said receiving conveyor.
